(57) **CLAIM**

The ornamental design for a dotted zipper hoodie, as shown and described.

DESCRIPTION

FIG. 1 is a perspective view of a dotted zipper hoodie showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of FIG. 1; and,

FIG. 10 is a partial enlarged view of FIG. 1.

The small broken lines shown in the drawings depict portions of the dotted zipper hoodie that forms no part of the claimed invention. The medium dash broken lines in the FIGS. 9 and 10 depict the boundaries of the enlargements that form no part of the claimed design.
